Albert Johnson INVENTOR.
BY
Albert Johnson ATTORNEY.

UNITED STATES PATENT OFFICE.

ALBERT JOHNSON, OF LOS ANGELES, CALIFORNIA, ASSIGNOR OF ONE-FOURTH TO
L. V. HUGHES AND H. E. HUGHES, BOTH OF LOS ANGELES, CALIFORNIA.

DRAFT CONTROL FOR LOCOMOTIVES.

Application filed July 28, 1926. Serial No. 125,345.

My invention relates to draft control for locomotives and other steam generating plants and it has for its principal object to provide in combination with a fire box and the door thereof one or more baffle members or deflectors for regulating and directing the air supply to the fire box in such a way that a more perfect combustion takes place and takes place in the upper part of the fire box and is directed through the upper or super heating tubes of the boiler, thus operating to give greater efficiency in the creation of steam, with a saving of fuel.

Other objects and advantages will appear from the following description of one embodiment of my invention shown on the accompanying sheet of drawings, which I will now describe.

Figure 1 is a perspective view of a portion of a fire box and boiler, with a section thereof broken away and shown in section, to show the general construction and arrangement; and

Figure 2 is a vertical sectional view through the door of the fire box with my invention applied thereto.

Referring now in detail to the drawings, the invention as here embodied for purposes of description, includes a fire box, 1, with oil burner, 2, therein, and with the boiler tubes, 3, 3, including the upper or larger tubes, 4, 4, referred to as the super-heating tubes. The mechanism so far referred to is of well known construction and can be of any desired type, forming no part of the invention, except as the invention is applied to and used in connection therewith. There is also the usual air inlet and door, as at 6. The main door is designated 7, hinged at 8, with latch, 9, and covers the main opening or door frame, seen at 10.

My invention as here illustrated includes a base member or plate, 11, secured just inside of said door frame 10, and constituting an anchorage for a baffle member 12, hingedly connected to said base member, 11, as at 13, said baffle member inclining upwardly and rearwardly within the fire box, opposite the door opening, and held in place by means of chains, as 14, which can be shortened or lengthened as desired. Said base member, 11, is secured on top of the fire wall, W, and the baffle member 12, hinged thereto at its lower side, can be

moved toward and from the door opening, 55 10, as will be clear from the drawings.

The door, 7, is provided with an opening, 10^a, and two side wings, 15, 15, are preferably cast or formed as a part of said door, 7, at the opposite sides of the door opening, 60 and between said side wings, 15, 15, hinged at its top edge, as at 16, 16, between said side wings, is a draft regulator door, 17, with a peek hole, 18, and cover, 19, therefor. A pivoted ratchet bar, 20, extends through 65 a hole, 21, in said door, 17, by which said door can be opened outwardly and held in any desired position, as clearly shown in Fig. 2. Said ratchet bar, 20, being pivotally connected with the main door, 7, as 70 at 20'.

I have not shown any fire brick or other lining for said fire box and said baffle member, 12, but it will be understood that such protection as may be wise can be used.

The air supply is admitted under the draft regulating door, 17, through the main door opening, 10^a, and is directed upwardly toward the upper part of the fire box, while the combustible gases are directed upwardly 80 along the under side of the baffle member, 12, the combustion taking place in the upper part of the fire box as the mixture of said gases and air takes place, thus creating intensified heat in the upper part, or the 85 top of the fire box, and back through the super-heating tubes, 4, 4.

I have also shown said baffle member, 12, provided with a peek hole, 22, and with a series of angularly disposed holes, 23, up 90 through which the combustion gases and heat are forced to meet the air currents above said baffle member.

Thus I have provided an efficient means for causing increased heat in the fire box 95 because of the better combustion, and therefore making the boiler more efficient in the development steam, with a saving of both fuel and water, due to the fact that more heat is secured from the fuel and steam of 100 a drier nature is produced.

I do not limit the invention to the details of construction and arrangement shown for descriptive purposes, realizing that changes can be made without departing from the 105 spirit of the invention, except as I may be limited by the hereto appended claims.

I claim:

1. In combination with a locomotive fire box and boiler having boiler tubes opening into said fire box, an oil burner in said fire box below said boiler and discharging into said fire box, means for admitting air into said fire box for combustion with the products from said oil burner, a door into said fire box above said oil burner level, and an adjustable baffle member within said fire box inwardly from said door, said baffle member being positioned in an inclined manner from within the fire box, opposite said door, upwardly and inwardly toward the upper boiler tubes for the purpose of directing the products of combustion from said oil burner and said air admitting means into said upper boiler tubes.
2. In combination with a locomotive boiler and fire box, with boiler tubes opening into said fire box, an oil burner in the lower

part of said fire box, air inlet means in the lower part of said fire box, a door frame and door into said fire box above said oil burner level, a baffle member adjustably connected at its lower edge to the innermost part of 25 said door frame and projecting upwardly and inwardly toward said boiler tubes in the upper part of said fire box, to deflect and direct the heat and products of combustion from said oil burner and said air 30 inlet means to said upper boiler tubes, and means for adjusting said baffle member to different angles for directing said heat and products of combustion to the upper boiler tubes, substantially as shown and described. 35

Signed at Los Angeles, Los Angeles county, California, this 22d day of July, 1926.

ALBERT JOHNSON.
